United States Patent Office.

JOHN L. SHILLITO AND WILLIAM M. WALKER, OF WELLSVILLE PENNSYLVANIA.

Letters Patent No. 90,399, dated May 25, 1869.

IMPROVED REIN-HOLDER.

The Schedule referred to in these Letters Patent and making part of the same.

To all whom it may concern:

Be it known that we, JOHN L. SHILLITO and WILLIAM M. WALKER, of Wellsville, in the county of York, and in the State of Pennsylvania, have invented certain new and useful Improvements in Line-Holders; and do hereby declare that the following is a full, clear, and exact description thereof, reference being had to the accompanying drawing, making a part of this specification, in which—

Figure 1 represents a side elevation of our improved holder; and

Figure 2, a vertical cross-section of the same on the line xx of fig. 1.

Letters of like name and kind refer to like parts in each of the figures.

Our invention relates to a class of devices used for the purpose of securing, or holding to the carriage the lines, or reins of a horse when not in use; and

It consists of a hinged clasp, secured by means of a spring-catch at its free end, and provided, upon its under side, with a rubber pad, corresponding in size and shape with a similar pad secured to the frame of said holder, between which the reins are clasped, when desired.

In annexed drawing—

A represents the frame of the holder, consisting of a flat piece of metal, three-fourths of an inch thick, and two inches wide, having two vertical parallel edges, and pointed at its lower side, as shown in fig. 1.

Said frame is bifurcated horizontally from edge to edge, (as shown in fig. 2,) so as to permit of its being passed over the upper edge of a dash-board, and is provided with suitable holes, xx , through which screws may be placed, for the purpose of securing the frame thereto.

Within the upper side or edge of the frame A, is a recess, B, one-half of an inch deep, and one and one-fourth inch long, the bottom of which is recessed out so as to contain a rubber pad, C.

A clasp, D, is hinged to the upper left-hand corner of said frame, and its free end shuts down into the opposite corner of the same, where it is secured by means of a spring-catch, a , engaging with a detent, d , at-

tached to and projecting downward from said clasp, the catch being released from engagement with said detent by means of a stud, c , projecting horizontally from the former.

The lower side of the clasp D is provided with a recess, which contains a rubber pad, d , corresponding in size and shape with that in the frame, so that when said clasp is closed, there is left, between said rubber pads, a space, which is intended to be a little less in width vertically than the thickness of the lines which are to be held, so that when said lines are placed within said space, and the clasp pressed down and secured, they shall be firmly held.

In order that lines of different thickness may be accommodated, the recess containing the lower pad is made somewhat deeper than is ordinarily required, so as to receive a number of shives of thin metal, or leather, by the addition or removal of which, said pad may be raised or lowered, and the space between the pads correspondingly changed.

This device can be readily attached to the dash-board of a carriage, or sleigh, and furnishes a secure and convenient means whereby the lines, or reins may be prevented from being drawn down upon the ground by the horse, it being only necessary to press against the stud c and release the clasp, which flies open by the pressure of the rubber, and permits the insertion of the lines, which are secured by closing said clasp.

Having thus fully set forth the nature and merits of our invention,

What we claim as new, and desire to secure by Letters Patent, is—

As a new article of manufacture, the within-described line-holder, consisting of the bifurcated frame A, clasp D, spring-catch a , detent d , and rubber pads c and d , substantially as and for the purpose shown.

In testimony that we claim the foregoing, we have hereunto set our hands, this 15th day of April, 1869.

JOHN L. SHILLITO.

WM. M. WALKER.
